UNITED STATES PATENT OFFICE.

JOSEPH SANDY, OF MINNEAPOLIS, MINNESOTA.

DRIFTING-VALVE FOR LOCOMOTIVES.

1,078,065.

Specification of Letters Patent.

Patented Nov. 11, 1913.

Application filed August 17, 1910. Serial No. 577,651.

To all whom it may concern:

Be it known that I, JOSEPH SANDY, a citizen of the United States, residing at Minneapolis, in the county of Hennepin and State of Minnesota, have invented certain new and useful Improvements in Drifting-Valves for Locomotives; and I do hereby declare the following to be a full, clear, and exact description of the invention, such as will enable others skilled in the art to which it appertains to make and use the same.

My invention has for its object to provide a simplified and improved drift valve mechanism for locomotives, and to this end the invention consists of the novel devices and combinations of devices hereinafter described and defined in the claims.

It is a well known fact that when a locomotive is drifting, that is, running without a supply of steam in its cylinders, as in running down grades, its cylinders and pistons operate as pumps so that the air will be sucked or pumped into the cylinders. This is objectionable for several reasons, among which may be mentioned the fact that the cold air thus drawn into the cylinders will unevenly contract the same and the cylinders must again be warmed up by the introduction of steam before the engine will again run under normal efficiency. When the steam is cut off, the cylinders are not kept properly lubricated, and furthermore, to make the matter worse, the air pumped into the cylinders will very frequently carry considerable dust or dirt which grinds the cylinders at a time when they are not lubricated.

My invention provides an extremely simple and efficient valve mechanism and connections, whereby, when an engine is drifting, an auxiliary supply of steam to the cylinders will be afforded, thus maintaining the proper lubrication of the cylinders and pistons when drifting or when the engine is running idle.

In the accompanying drawings which illustrate the invention, like characters indicate like parts throughout the several views.

Referring to the drawings: Figure 1 is a fragmentary view partly in front elevation and partly in transverse vertical section, illustrating my invention; Fig. 2 is a transverse vertical section taken through the valve and casing of the drift valve mechanism; Fig. 3 a horizontal section taken

on the line $x^3 x^3$ of Fig. 2; and Fig. 4 is a horizontal section taken approximately on the line $x^4 x^4$ of Fig. 2.

The numeral 1 indicates the boiler, the 60 numeral 2 one of the cylinder brackets, the numeral 3 one of the cylinders, the numeral 4 one of the steam chests, the numeral 5 one of the steam pipes, and the numeral 6 portions of one of the side frames of the locomotive, which parts are of standard or of any suitable construction.

My invention provides an auxiliary steam supply conduit or by passage which leads from the boiler to the steam chest and is independent of the normal or main steam supply pipe 5. This auxiliary passage, as shown, comprises a pipe 7, a valve casing which is shown, and made up of two sections 8 and 9 connected by threaded engagement 75 at 10. The upper section 9 is provided with a laterally projecting neck 11 which, as shown, is directly connected to the steam chest 4, and is provided internally with a cylindrical seat 12, the purpose of which 80 will presently appear. The lower section 8 is provided with a cylindrical seat 13 that is axially aligned with the cylindrical seat 12 but is of much less diameter. The steam pipe 7 is connected with the section 8 and 85 communicates with a port 14 in one side of the intermediate portion of the cylindrical seat 13. The upper and lower portions of the cylindrical seat 13 are connected by ports 15 and 16 and a conduit 17. Working 90 in the cylindrical seat 13 is a tubular valve 18 provided with upper and lower piston-like flanges 19 and 20.

Working in the cylindrical seat 12 and secured to the upper end of the valve 18 is 95 a valve actuating head 21 which, as shown, is in the form of a piston head. The axial passage through the tubular valve 18 is, as shown, normally closed by the gravity seated check valve 22 mounted in the head 100 21. This check valve 22 will permit steam to flow upward through the valve 18, but checks the reverse flow.

The numeral 23 indicates a normally closed drip cock which is connected to the 105 lower portion of the cylindrical seat 13.

The steam pipe 7 preferably leads from the dome of the locomotive boiler, and is shown as provided with a normally open valve 24 which, in practice, would advisably 110 be located in the engineer's cab so that it may be readily manipulated to close the aux-

2

slipper steam conduit when desired and thereby throw the drift valve mechanism out of action. When the valve 24 is open, however, the drift valve mechanism is automatic in its action, and the operation thereof will be substantially as follows:—When the locomotive is driven in the ordinary way, by steam supplied to its cylinders through steam pipes 5 and steam chest 4, the live steam from the chest will enter the upper section 9 of the valve casing, and acting on the upper surface of the head 21 will hold the valve 18 in the normal position shown in Fig. 2. In this normal position of the said valve, the head 21 will be tightly seated, preferably on a ground seat 25 formed on the upper portion of the casing section 9. Also at such times the valve flanges 19 and 20 will be on opposite sides of the steam admission port 14, and between the ports 15 and 16. The steam which is normally admitted into the seat 13, will be caged between the flanges 19 and 20 and will have no tendency to move the valve 18 in either direction. When the steam supply to the chests through the steam pipe 5 is cut off, by manipulation of the throttle valve in the engineer's cab, and the engine is then driven forward, either by momentum or by gravity when running down grade, a suction or partial vacuum will be produced in the steam chest and this acting on the valve head 21 will raise the valve 18 into a position in which its flange 20 will be above the port 16 and its flanges 19 and 20, one on each side of the admission port 14. This will permit live steam conducted by the pipe 7 to the port 14, to pass from thence to the port 16, through the conduit 17 and port 15 to the lower end of the seat 13, and from thence upward to the axial passage in the valve 18, (the valve 22 being then lifted by steam pressure) into the upper section 9 of the valve casing, and from thence through the neck 11 thereof, into the steam chest. When the valve has been raised, as just stated, the live steam pressure on the lower end, thereof, will be effective to hold the said valve in its raised position, until live steam is again admitted into the steam chest, through the pipes 5, by opening of the throttle valve, whereupon, the steam pressure from the relatively large area of the valve head 9 will force the said valve 18 back into its normal position shown in the drawings.

The efficiency of the device above described has been demonstrated in practice. It may be applied to the steam chest of a locomotive and connected to the boiler at comparatively small cost. Its use greatly increases the life of the cylinders and pistons of a locomotive by maintaining lubrication thereof while the engine is drifting and while the main supply of steam is cut off from the cylinders.

What I claim is:

1. In a locomotive, auxiliary steam supply conduits connecting the boiler to the steam chests, independently of the throttle controlled normal steam supply connections, and differential valve casings and co-operating differential valves interposed in said auxiliary steam supply conduits, said valves having their large ends subject to steam chest pressure and having a balanced portion normally closing said auxiliary conduit but arranged to be moved into a position to open up said auxiliary conduits, by suction or partial vacuum produced in the cylinder and steam chest and acting on the large ends of said differential valves, when the engine is drifting.

2. In a locomotive, auxiliary steam supply conduits connecting the boiler to the steam chests, independently of the throttle controlled normal steam supply connections, and differential valve casings and co-operating differential valves interposed in said auxiliary steam supply conduits, said valves having their large ends subject to steam chest pressure and having a balanced portion normally closing said auxiliary conduit but arranged to be moved into a position to open up said auxiliary conduits, by suction or partial vacuum produced in the cylinder and steam chest and acting on the large ends of said differential valves, when the engine is drifting, the said differential valves having axial passages therethrough, equipped with check valves and constituting parts of said auxiliary steam supply conduits, which check valves are mounted in said differential valves.

In testimony whereof I affix my signature in presence of two witnesses.

JOSEPH SANDY.
